3 Claims. (Cl. 235—92)

My invention relates to totalizers and is concerned particularly with improved means for making common registering apparatus or conductors leading thereto available to a plurality of ticket issuing or like machines.

Systems are known in which a rotary switch or its equivalent renders each of a plurality of ticket issuing machines effective in turn for the transmission of bet signals over a common group of conductors to registering equipment. In systems of this kind the switch passes through positions corresponding to the various machines in a definite cyclic order, whether or not a particular machine has a bet to be collected when the switch reaches its position. Time is therefore lost owing to the inability of the switch to pass instantaneously through positions corresponding to machines which have no bets to transmit.

According to my invention, I provide collecting means which take up positions corresponding only to those machines having bets to be collected. Thus, after a bet has been collected from one machine, the next machine in order having a bet to transmit will be made effective immediately, there being no movement of the collecting means corresponding to that performed by the switch in the systems already referred to in moving through positions associated with machines having no bets to be collected.

In order to attain this end I may associate one or more relays with each machine and provide a circuit such that a potential is extended through contacts of relays associated with machines having no bets to be collected to a winding of a relay associated with the next machine having a bet to be collected. Relays associated with machines having no bets to be collected are therefore inoperative and a signal which results in the collection of a bet may be extended forward directly to a relay associated with the appropriate machine.

Although the relays do not operate in any predetermined order, the arrangement of the machines themselves may ensure that a machine having a bet to be collected is made effective in its turn to transmit a bet signal. Since relays are operated only when bets are to be collected, reduction in wear and current consumption, besides the saving in time already referred to, is effected.

One of the relays associated with a machine may be adapted, upon operation, to make that machine effective for transmitting a bet signal to the common registering equipment. The operation of this relay may be dependent upon a circuit prepared when a bet key is depressed, the op-

eration being delayed if necessary until a preceding bet has been registered.

Control signals may be transmitted over a chain circuit extending through normally closed contacts of a relay associated with each machine. When a bet key is pressed at a particular machine, this relay may operate, open the chain circuit, and connect to one side thereof, the relay which must operate before the machine can be made effective for the transmission of a signal to the common registering equipment. The operating potential for this latter relay may be applied at one end of the chain circuit, at a particular point therein, or at the machine at which the preceding bet originated. The chain circuit may or may not be endless.

If desired, the arrangement may be such that when the common conductors have been made available to a particular machine they cannot again be made available thereto while any other machine which has not had its turn is waiting to use them. For this purpose a relay at each machine may operate when the common wires have been made available to that machine and lock up under the control of a common clearing relay until other waiting machines have had their turn.

In this manner the machines transmit their bets successively, no machine having an opportunity to transmit a second bet until all the waiting machines that have not had their turn have been dealt with.

Means for testing the contacts in the chain circuit may be provided and may be made operative automatically. A fault alarm may be provided if desired.

Subsidiary features of my invention will become apparent from the following description of methods of carrying it into effect, and reference should be made to the accompanying drawings, in which:

Figure 1 shows the circuit arrangements at a ticket machine for controlling the counting apparatus.

Figure 2 shows the circuit of relays associated with a ticket machine, part of the chain circuit associated with other ticket machines, and certain common apparatus.

Figure 3 shows a plug and jack, and the circuit of associated relay equipment by which a conductor, such as 2, corresponding to a particular competitor, is given access to a particular adding equipment.

Figure 4 shows the circuit of adding or registering equipment.

Figure 5 is a diagram showing the way in which Figures 1 to 4 inclusive should be arranged.

Figure 6 is a skeleton chain circuit showing an alternative to Figure 2.

5 Figure 7 represents the general arrangement of a totalizer system incorporating the present invention. The assembled sections of apparatus are represented by rectangles in which are printed the reference letters of the different relays and other elements (shown by the same references in Figures 1-6) which they contain. Notes beside the various elements and connecting wires indicate in certain cases the manner of their connection.

- ing of relay A, contact *pb4*, terminal W, resistance RW to battery. Relay CT remains operated and relay A operates and is held from earth, contacts *ti4*, *c5*, *st4* and *a2*, left-hand winding of relay A to battery. Relay CD releases owing to the operation of contact *a1* unless its circuit is completed by way of the relay equipment associated with another ticket machine awaiting to make a bet and having its associated ST relay operated. In the latter case the circuit of relay CT will be extended by way of contacts *bs1* and *a3* to a connecting relay associated with another machine. If this machine is waiting to make a win bet, its connecting relay will not operate owing to the short-circuiting earth potential applied by contact *a6* of the previously operated connecting relay by way of contact *pb4* to terminal W associated with the common resistance for win bets RW.
- If the competitor upon which the bet is made is an actual runner, the plug P' (Figure 3) associated with an adding equipment will be inserted into jack J thus disconnecting conductor 2 from conductor 3 and extending it to access relays WA and PA. A circuit is thus closed from earth, resistance R3 (Figure 2), contacts *pb5*, *ho1*, *ti3* and *a9*, conductor 4, bet key contact *h1* (Figure 1), conductor 2, jack J, (Figure 3), plug P', contact *pa1*, relay WA to battery. Relay WA operates and closes contacts, one of which is shown at *wa3*, associated with the various denominational sections of the adding equipment for win bets on the competitor in question. Contact *wa2* applies earth potential to terminal W.
- A circuit is now closed from earth, contacts *ti4* (Figure 2), *c5*, *st4*, *a4* and *pb3*, conductor 5 contacts *tt1* (Figure 4), *tz1* and *tr1*, conductor 6, contact *wa3* (Figure 3), conductor 7, contacts *it1* (Figure 4) *iz1* and *ir1*, upper winding of relay IM to battery. Relay IM operates and locks by way of stake wire conductor 8 in a circuit from earth, contacts *ti5* (Figure 2), *c6* and *st7*, left-hand winding of relay TI, contacts *a5* and *pb7*, conductor 8, contact *im1*, lower winding of relay IM to battery. Relay TI operates and is held operated in a circuit from earth, contact *u* (Figure 1), relay T, conductor 1, contact *ti1* (Figure 2), right-hand winding of relay TI to battery. Relay T now receives sufficient current to operate and close a contact whereby the circuit of a ticket issuing machine is completed and the machine set into operation. This machine may for example be of known kind, such as described in the specification of British Patent No. 289,901 filed on November 2, 1926.
- Relay IM is held operated on its upper winding from earth, interrupter contact *idm1*, contacts *is2* and *im2*, resistance R4, upper winding of relay IM to battery, and also from earth at interrupter contact *tdm1* by way of contacts *ts2*, *im3*, *im2* and resistance R4.
- Contact *im4* maintains earth potential on terminal W by way of conductor 9. Contact *im5* closes an obvious circuit for the magnet of switch IDM and relay IA in parallel. The magnet energizes and opens contact *idm1*, thereby removing one of the sources of earth potential holding relay IM, but it does not move its wipers. Relay IA operates and contact *ia1* prepares a circuit for relay IP; the resultant circuit operations are only of importance under abnormal conditions which will be described hereinafter. Contact *im6* closes an obvious circuit for the magnet of switch TDM and relay TA in parallel. The magnet opens interrupter contact *tdm1*, thereby removing the

second earth potential holding relay IM, and relay TA operates and prepares a circuit, not shown, similar to that prepared by relay IA at contact *ia1*.

From the above it will be seen that relay IM can release only after contact *ti5* (Figure 2) and both interrupter contacts *idm1* and *tdm1* (Figure 3) of the registering switches for win bets on the individual competitor and the totals have been operated. When relay IM releases, contacts *im5* and *im6* open the circuit of the magnets of the registering switches, which advance their wipers one step and control the indicators showing the number of win bets registered on the individual competitor and on the totals in known manner as described, for example, in the specification of British Patent No. 331,500 filed on March 28th, 1929, and as illustrated in Figures 18, 19 and 20 thereof.

Owing to the operation of relay TI (Figure 2) relay ST releases, its circuit being opened at contact *ti2*. The chain circuit is now maintained at contact *st3* independently of contact *a3*. Contact *ti3* opens the circuit of relay WA; contact *ti4* opens the previously traced holding circuit of relay A and also completes an obvious circuit for relay HO. Relays WA and A release and relay HO operates.

One source of earth potential on terminal W is removed by the relapse of contact *a6* but if earth potential is maintained from some other source, such as contact *im4* (Figure 4) or *wd2* (Figure 3), another A relay cannot operate by way of the common resistance RW. Normally, relays WA and IM release and relay TI operates in the manner described; the earth potential is thus removed so that another bet may be accepted.

The operation of the ticket machine causes contact *u* to open, a bet ticket to be issued, and the bet key and win and place key to release. Contact *u* opens the circuit of relay T and the right-hand winding of relay TI. Relays T and TI release and contact *ti4* opens the operating circuit of relay HO. If relay HO is not held on its upper winding it will release and contact *ho3* will prepare the circuit of relay ST so that the ticket machine can make another bet immediately. If, however, other machines are waiting to make bets, relay HO will remain locked to the earth at contact *cd1*. Relay CD releases when no other machines associated with unoperated HO relays are waiting to make bets. Relay HO thus prevents the acceptance of a second bet from the same machine until the other machines associated with the same chain have been given an opportunity of making a bet. Thereafter, relays CD and HO release and contact *ho3* prepares the circuit of relay ST.

If bets are made at two or more ticket machines when the associated HO relays have not been released, and if the time elements of the relays associated with the various machines are substantially equal, which is the condition met with in practice, the next ticket machine to register after the release of the HO relays will be determined by the position of the *st3* contacts in the chain circuit, preference being given to the machine having its associated *st3* contacts nearest to relay CT. A similar preference is given to waiting ticket machines when their HO relays are unoperated.

If a registering switch such as IDM is energized at a time when a transfer must be made to a higher denomination, a transfer relay, such as

relay IZA, associated with the higher denomination is operated. If the bets are counted in a decimal system of notation the lower winding of relay IZA is connected to a contact associated with wiper $idm3$ so that its circuit is completed when contact $im5$ closes in response to each tenth bet. Relay IZA corresponds to relay IZ in the lower denomination. Thus when a transfer is made from a denomination lower than that associated with relay IZ, the latter operates by way of its lower winding and locks by way of its upper winding from earth, contacts $iz3$, $iz2$ and $iz6$.

Contact $iz3$ closes a circuit from earth, contacts $idm1$, $is2$, $im2$, $iz3$, relay IR to battery. Relay IR operates and contact $ir2$ closes an obvious circuit for the magnet of registering switch IDM and relay IA in parallel. Contact $ir6$, which is a late opening contact, opens the circuit of the upper winding of relay IZ. The circuit of the lower winding is opened when the registering switch in the lower denomination moves off its ninth contact. Relay IR is held, prior to the release of relay IZ from the earth at contact $iz3$ by way of contacts $iz2$ and $ir3$. It is also held from the earth at interrupter contact $idm1$ by way of contact $ir4$. When these holding circuits have both been opened by the release of relay IZ and the operation of the magnet of switch IDM, at contacts $iz2$ and $idm1$ respectively, relay IR releases, thereby causing the release of relay IA and the registering switch. The latter moves its wipers and causes the indicator to be advanced by an amount corresponding to the transfer.

Contacts $iz4$ and $ir3$ are connected to a branch of the circuit for holding the IM relay in the lower denomination. These contacts correspond to contacts $iza4$ and $ira5$ of the transfer relays in the next higher denomination. Upon the operation of relay IZA, relay IM is held to the earth at contact $ira5$ by way of contact $iza4$. When, however, the circuit of the magnet in the higher denomination is completed, contact $ira5$ operates and removes the holding earth. Relay IM releases after all holding earths have been removed and causes the advance of registering switch IDM. Wiper $idm3$ opens the circuit of the lower winding of relay IZA. Relay IZA releases when the circuit of both its windings have been opened. If for any reason contact $ira5$ does not fall back immediately, owing, for example, to its associated registering switch sticking, relay IM will be held when it operates for the next bet. Hence acceptance of further win bets will be prevented whilst contact $ira5$ remains operated.

A somewhat similar transfer arrangement is provided for the totals registering switch. The transfer relay in the higher denomination is shown at TZA and corresponds to relay TZ. Relay TZ operates by way of the switch contact in the lower denomination over its lower winding and holds on its other winding by way of contacts $ts3$, $tz2$ and $tr5$. Contact $tz3$ closes a circuit for relay TR from earth, contact $tz3$, upper winding of relay TR, resistance $R5$ to battery. Relay TR operates and is held operated by its lower winding to the earth at contact $tdm1$ by way of contacts $tr3$ and $ts2$. Contact $tr2$ completes the circuit for relay TA and the magnet of registering switch TDM. The latter energizes and contact $tdm1$ opens the circuit of the lower winding of relay TR. Relay TZ releases as soon as the circuit of its upper and lower windings are opened by contact $tr5$ and by the advance of the registering switch of the lower denomination respectively. Relay TR releases when the circuits

of its upper and lower windings are opened by contacts $tz3$ and $tdm1$, and causes the release of relay TA and the release of the magnet and advance of the wipers of switch TDM. During the transfer, contacts $tz4$ and $tr5$, which correspond to contacts $ta4$ and $tr5$ in the next higher denomination, control the operation of relay IM in a similar manner to that explained in relation to contacts $iz4$ and $ir5$, or $iza4$ and $ira5$.

It follows from the foregoing description that provided there is only one set of connecting relays A, A^1 . . . . A^n (Figure 2), and chain contacts $st3$, $st4$, ... $stn3$, only one win bet can be registered on the totalizer at a time because the operation of one connecting relay when a win bet is made prevents the operation of any other connecting relay associated with another machine waiting to register a win bet. Such relay when once operated is held so as to ensure registration of the bet and it is not released until the apparatus is ready for accepting the next win bet. It may, however, be desirable to provide more than one set of connecting relays and chain contacts. A separate set may, for example, be provided for each denomination and there may be separate WA relays and PA relays for each set.

Two win bets may then be registered in different denominations simultaneously. A bet must not, however, be registered at the same time as a transfer on the same denomination; for this reason contacts $ir1$, $iz1$, $tr1$ and $tz1$ are included in the circuit of relay IM to prevent its operation if there is a transfer either on the associated or totals equipment of the same denomination. On the other hand, once relay IM has operated a transfer cannot be effected on the individual competitor because contact $im2$ opens the operating circuit of relay IR, and it cannot be effected on the totals because contact $im6$ short-circuits the operating winding of relay TR. Should relays IM and TZ operate simultaneously, switch TDM will first be energized from the earth at contact $im6$, relay TZ remaining locked until the operation of relay TR, which can only take place after the release of relay IM. Similarly, if relays IM and IZ operate simultaneously, switch IDM will first be energized from the earth at contact $im5$, relay IZ remaining locked until the operation of relay IR which can only follow the release of relay IM.

Competitor numbers not used in a particular event (non-runner numbers) do not have the corresponding jacks J (Figure 3) plugged through to an adding equipment. If a machine is accidentally operated for a win bet on a non-runner, the initial circuit operations are the same as those previously described, that is, relay ST operates and is followed by relay A, but contact $a9$ then closes a circuit from earth, resistance $R3$, contacts $pb5$, $ho1$, $ti5$ and $a9$, conductor 4, contact $h1$ (Figure 1), conductor 2, jack J (Figure 3), conductor 3, contact npl , relay NW to battery.

Relay NW operates and contact $nw2$ maintains an earth potential on terminal W. Contact $nw1$ extends the earth potential on conductor 3 to terminal NRW, which is the same as the similarly marked terminal in Figure 2, and thence by way of contacts $pb2$, $a1$ and $st5$, upper winding of relay C, contact pbl , resistance $R6$ to battery. Relay C operates and holds in a circuit from earth, resistance $R3$, contacts $pb5$, $st2$ and $c1$, lower winding of relay C, contact pbl , resistance $R6$ to battery.

Contact $c2$ closes a circuit from earth, lamp $L2$ (Figure 1), conductor 10, contact $c2$, resistance 75

R7 to battery. Contact c4 extends the earth on conductor 1 to the lower winding of relay HO. Relay HO operates but the operation of contact c1 prevents the possibility of this relay being held by way of its upper winding. Relays NW and ST release because their circuits are opened by contacts ho1 and ho3 respectively and relay A releases because its circuit is opened by contact c5. Betting can now continue from other ticket machines.

Relay T (Figure 1) cannot operate in series with relay HO, hence the ticket machine remains locked up. Lamp L2, however, glows and indicates that the bet cannot be accepted, and the operator, noting the lamp alight, unlocks the machine mechanically, thereby opening contacts u and h1.

Contact u opens the circuit of relay HO. Relay HO releases and at contact ho1 opens the holding circuit of relay C. Relay C releases and extinguishes lamp L2 (Figure 1).

If a place bet is made, win and place key K2 is moved into the "place" position and then the required bet key is operated. Earth is now extended from key K2 by way of conductor 11 to place bet relay PB (Figure 2). Relay ST operates to the earth on conductor 1 as in the case of a win bet and relay A operates as before except that it is now fed from battery by way of resistance RP, terminal P and contact pb4, instead of from battery by way of resistance RW and terminal W.

Relay A locks on its left-hand winding to the earth at contact ti4 as before, and the earth at contact a6 short-circuits its other winding; it also earths terminal P so as to prevent another connecting relay belonging to the same chain circuit from operating in response to a place bet.

Contact a1 closes a circuit from earth, contacts a1 and pb8, common relay PD to battery. Relay PD has a number of contacts that apply earth potential to relays such as PA and NP (Figure 3). Accordingly, if the bet is for a runner, a circuit will be closed for the associated PA relay from earth, contact pd1, conductor 12, relay PA (Figure 3), contact wa1, plug P, jack J, conductor 2, bet key contact h1 (Figure 1), conductor 4, contacts a9 (Figure 2), ti3, ho1 and pb1, resistance R6 to battery.

Relay PA operates and it should be noted that owing to the operation of contacts pb1 and pb5, the current is in the reverse direction to the current that flows when relay WA operates for a win bet. Subsequent operations are similar to those already described for a win bet, extension in this case being made by way of the operated contacts pb3 and pb7 and the contact of relay PA corresponding to contact wa3 associated with adding equipment for place bets similar to that shown in Figure 4. The tm4 contacts and pa2 contacts, when closed, earth terminal P so as to prevent the operation of another relay for a place bet.

In due course the place bet is registered and a place ticket issued by the machine. Relay PB releases after the win and place key has been restored; relay PD releases after the relapse of contact a1, unless it is held from some other equipment, and removes the earth from all PA relays. This prevents these relays from chattering continuously in series with the WA relays by way of contacts wa1 and pa1.

From the foregoing description it will be evident that win and place bets on different competitors can be registered simultaneously because

the operation of a connecting relay for a win bet does not affect the operating circuit of a connecting relay for a place bet and vice versa, the chain circuit being completed by way of contact a3 prior to the release of contact st3. If win and place bets are made at the same time on the same competitor, two connecting relays are again operated, but in this case the bets are registered one after the other. This is because a WA and a PA relay cannot both be fully operated together, for if one relay fully operates it definitely breaks the circuit of the other relay.

Thus when relay WA fully operates it breaks the circuit of relay PA at contacts wa1, while when relay PA operates the circuit of relay WA is broken at contacts pa1. If the circuits of both relays are completed simultaneously, one relay in practice operates before the other owing to a slight difference in the characteristics which invariably exists, while if desired this effect may be ensured by adjusting the relays PA and WA so that one is definitely slower in operation than the other.

If a place bet be made on a non-runner, relay NP operates instead of relay PA, its circuit being completed from earth, contact pd2 (Figure 2), conductor 16, relay NP, contact nw1, conductor 3, jack J, and thence to the battery potential on conductor 2 by way of part of the circuit previously traced. This battery potential is extended by contact np1 to the non-runner terminal NRP corresponding to terminal NRP in Figure 2, and thence by way of contacts pb2, a7 and st5, the upper winding of relay C, contact pb6, resistance R3 to earth. Contact np2 maintains earth potential on terminal P.

Relay C operates and locks, the subsequent circuit operations being similar to those described in the case of a win bet on a non-runner. If relay PD is not held from some other machine it will release when contact a1 falls back and remove the earth potential from conductors such as 16 and 12 leading to the NP and PA relays. When the operator, noting lamp L2 glowing, releases the ticket machine, the win and place key returns to normal and removes the earth from conductor 11 thus causing the release of relay PB.

When it is desired to re-set the indicators and registering switches, key K1 (Figure 2) is released. This causes the release of relays BS, TS and IS. Contacts bs1 and bs4 open the circuits of relays CT and CF respectively and these relays slowly release. Contact bs3 removes the starting earth from the pulsing arrangement and the relapse of contact bs5 extinguishes lamp L1.

If the registering switch TDM is in an off-normal position, the release of relay TS closes a circuit from earth, interrupter contact tdm1, contact ts2, wiper tdm2, the magnet of switch TDM and relay TA in parallel to battery. Switch TDM is therefore advanced under the influence of its interrupter contacts tdm1 in well known manner until it returns to a normal position, when the circuit of the magnet and relay TA is definitely opened by wiper tdm2. The relapse of contact ts1 causes relay TT to release and the relapse of contact ts4 opens the circuit of the indicator.

Similar operations take place in the individual adding equipments, contact is2 closing a homing circuit for switch IDM by way of wiper idm2, and relay IT releasing owing to the relapse of contact is1.

Various supervisory arrangements which are provided to indicate the presence of a fault and facilitate its location will now be described. If a

fault occurs, further irregular operation of the totalizator should be prevented. In order to achieve this end the fault may cause betting to be stopped. In any case it is desirable to provide 5 an alarm which automatically operates when a fault occurs.

If a contact in the chain circuit such as *st3* or *bs1* becomes dirty, relay *CT* will slowly release and short-circuit relay *CF* which in turn will also 10 slowly release. Contact *c3* then changes over, opening the circuit of lamp *L1* and closing a circuit from earth, contacts *bs5*, *c3*, *dw1* and *dpl*, lamp *L3*, relay *AS* to battery. Lamp *L1* is extinguished and lamp *L3* glows to indicate a fault 15 in the chain circuit. Relay *AS* operates and starts slow to operate sectional and main alarm circuits not shown.

If the circuit operations leading to the issue 20 of a ticket are unduly prolonged, the short-circuiting earth applied by contact *a8* to relay *CT* will eventually cause both this relay and relay *CF* to release. If a win bet is in progress, the release 25 of contact *c1* closes a circuit from earth, resistance *R3*, contacts *pb5*, *hol*, *ti3* and *a8*, lamp *L4*, contact *pb6*, relay *FW*, contacts *c1*, *pb2*, *a1* and *st5*, upper winding of relay *C*, contact *pbl*, resistance *R6* to battery.

Relay *C* does not receive sufficient current to 30 allow it to operate, but relay *FW* operates, and contact *fw1* closes an obvious circuit for auxiliary relay *DW*. Relay *DW* operates and contact *dws* shunts relay *FW* by resistance *R8*. This resistance is not low enough to cause relay *FW* to release or relay *C* to operate. The increased current through lamp *L4* will, however, cause it to 35 glow and localize the fault to the relay equipment associated with a particular ticket machine.

Contact *dw1* opens the circuit that would otherwise be closed for lamp *L3* and contact *dw2* completes a circuit for lamp *L6* from earth, contacts *bs5*, *c3* and *dw2*, lamp *L6*, relay *AS* to battery. Lamp *L6* glows and indicates a fault during the registration of a win bet, and relay *AS* operates to start the alarm. If key *K4* is now operated, 45 lamp *L4* will be short-circuited and sufficient current will flow through the upper winding of relay *C* for its operation. Relay *C* is then held to the earth at resistance *R3* by way of its lower winding and contacts *c3*, *st2* and *pb5*.

The operation of relay *C* causes operations to 50 take place similar to those described in the case of a bet on a non-runner; relay *A* releases and allows betting to proceed on other machines, and lamp *L2* glows as a signal to the operator to release the ticket machine.

Similar operations take place if the issue of a ticket for a place bet is unduly prolonged, but in 60 this case the operation of contacts *pb2* and *pb6* will bring in relay *FF*, by way of contact *c2*, instead of relay *FW*. Relay *FF* at contact *fp1* brings in relay *DP*. Relay *FF* is then shunted by way of contact *dp3* and resistance *R9*. Contact *dp2* brings in lamp *L5* to indicate that the 65 fault has been brought on during the registration of a place bet and contact *dpl* opens the circuit of lamp *L3*.

If the registration of a bet is unduly prolonged 70 because the registering switch fails to remove the earth from its interrupter contact, arrangements are provided whereby when betting restarts another bet intended to be registered by the switch in question causes relay *C* to operate immediately. Such failure may occur, for example, owing to a 75 switch sticking, or because the switch is held op-

erated for an unduly long period owing to a fault elsewhere.

Whenever the magnet of switch *IDM* is energized relay *IA* operates in a parallel circuit and contact *ia1* connects the left-hand winding of relay *IP* to terminal *S* by way of contact *iq3*. Sooner or later an earth potential pulse will be applied to terminal *S*, causing relay *IP* to operate if relay *IA* is still operated. So long as relay *IA* remains operated, relay *IP* will now be held in a 10 circuit from earth, contact *ia2*, right-hand winding of relay *IP*, contact *ip2*, right-hand winding of relay *IQ* to battery. Relay *IQ* does not, however, receive sufficient current to operate. After a definite period has elapsed, say $1\frac{1}{4}$ seconds, 15 since the application of the earth potential pulse on terminal *S*, a similar pulse is applied to terminal *Z*. Relay *IQ* will then operate on its left-hand winding by way of contact *ip1*, providing that relay *IP* has been held during the whole of the 20 period; this will be the case only if relay *IA* has remained operated.

When relay *IQ* operates, it holds to the earth at contact *ia2* by way of contact *iq2*; the latter contact short-circuits the right-hand winding of 25 relay *IP*. Relay *IP* therefore releases and contact *iq3* prevents its re-operation so long as relay *IQ* remains operated.

Owing to the operation of relay *IQ*, contact *iq1* opens the circuit of relay *IT*; relay *IT* releases and contacts such as *it1* open the operating 30 circuits of the *IM* relays of different denominations of the adding equipment relative to the same competitor. Further betting for a win on this competitor is therefore prevented and the circuit of an alarm may be closed by relay *IQ* so as to indicate the faulty adding equipment.

If a ticket machine is now operated in an attempt to make another bet on the same competitor, the earth potential on plug *P* (in the case of 40 a win bet), which holds relay *WA* operated, is extended by way of contact *wal*, conductor *14*, contact *it2* to terminal *NRW* (which is the same as terminal *NRW* on Figure 2) and thence by way of contacts *pb2*, *a1* and *st5*, upper winding 45 of relay *C*, contact *pbl* and resistance *R6* to battery. Relay *C* operates and holds, causing subsequent operations to take place whereby the ticket machine can be released by the operator as previously described.

If the faulty registering switch is associated 50 with place bets the operation of relay *PA* extends the battery potential on plug *P* by way of contact *pal*, conductor *15*, contact *it3* and terminal *NRP* (which is the same as terminal *NRP* on Figure 2), 55 thence by way of contacts *pb2*, *a1* and *st5*, upper winding of relay *C*, contact *pb5*, resistance *R3* to earth. Relay *C* operates and signals the fault condition to the ticket machine operator as before.

Suitable supervisory arrangements may also be 60 provided to deal with other faults occurring on the totalizator, such as contact between conductors corresponding to two different competitors.

The embodiment of the invention using the 65 circuit arrangement shown in Figure 6 will now be described. This figure does not show the complete circuit, which may be similar to that described in connection with Figure 2 with the exception of modifications that will be obvious to those skilled in the art. Letter references similar to those used in Figure 2 have been retained for relays that perform similar functions, as far as possible, although the actual circuit operations in certain cases necessarily vary in detail. 70 75

The chain circuit comprises a complete loop containing series break contacts of relays AA, AA¹, AA² . . . AAⁿ as well as contacts st³, st¹³, st²³ . . . stⁿ³. Relays corresponding to relays

- 5 ST and A are associated with other machines and will be referred to as relays ST¹, ST² . . . STⁿ and A¹, A² . . . Aⁿ. Some of their contacts are shown in the drawings. The operation of an AA relay closes the circuit of a connecting relay 10 10 A, which operates under conditions somewhat similar to those described for relay A in Figure 2. There is no hold-off feature and relay HO shown in Figure 2 is not required. An additional relay FO is provided in the supervisory 15 equipment in series with the chain circuit. The drawings should now be arranged so that Figure 6 takes the place of Figure 2 in Figure 5.

When the betting start relay operates, contact 20 bs¹ closes a circuit from earth, contact bs¹, relay FO, contacts aa¹, . . . aa²¹, aa¹¹, aa¹, st³, st¹³, st²³ . . . stⁿ³, fo¹, relay CT to battery. Relay CT operates and remains operated, unless the chain circuit is opened for a prolonged period owing to a fault, but relay FO can 25 not operate in series with relay CT.

If a win bet is made at a moment when no other machine is waiting for a bet to be accepted, the earth on conductor 1 completes the circuit of relay ST by way of contact ti². Relay ST 30 operates and contact st³ completes the circuit of relay AA from the earth at contact bs¹, relay FO, the aa¹ contacts, contacts st³ and c⁴, relay AA to battery. Relays FO and AA now operate. Contact aa³ completes a locking circuit 35 for relay AA, its initial operating circuit being opened by late opening contact aa¹. Contacts aa³ and aa¹ are not actually necessary in the case of this machine and are shown only for the sake of convenience. It will appear from 40 the following description, however, that corresponding contacts are necessary in the case of the other machines.

Upon the operation of relay AA, a circuit is closed from earth, contacts st¹, ti⁶, c¹, aa², lower 45 winding of connecting relay A, contacts aa⁴ and pb⁴, terminal W, resistance RW to battery. Relay A operates and locks on its upper winding by way of contact a². The earth potential at resistance R³ is now extended by way of contacts pb⁵, st², ti³ and a⁹ to conductor 4, thus 50 operating relay WA (Figure 3). The earth at contact ti⁴ which is extended by way of contacts c⁵, st⁴, a⁴ and pb³ to conductor 5 then causes the operation of relay IM (Figure 4), which at contact im¹ closes the circuit for relay 55 TI as already described.

Relay IM causes the bet to be registered, the circuit operations being similar to those previously described except that in this case contact im⁴ 60 bridges terminals W and WP (Figure 6) instead of being connected to earth. This connection short-circuits the operating winding of other connecting relays so long as contact pb⁴ is not operated, that is, provided the associated ticket 65 machine has not been operated for a place bet. Other contacts which have been described as earthing terminal W (for example, contacts wa² and nw²) are also connected so as to bridge terminals W and WP; hence a second connecting 70 relay associated with the same relay chain cannot operate to allow the acceptance of another win bet until registration has taken place. The operation of a connecting relay for a win bet itself short-circuits all other connecting relays 75 in the same chain except relays associated with

ticket machines operated for place bets, since contact a⁶ bridges terminals W and WP, which are common to all relay groups associated with the same chain circuit.

The closure of contact a³ bridges the upper and lower branches of the chain circuit, so that upon the operation of another ST relay the corresponding AA relay will operate. Thus, if relay ST² is operated, relay AA² operates. Relay AA² is followed by relay A², and when contact a²³ 10 closes, the upper and lower branches of the chain circuit are again bridged. If now relay ST has released, owing to the operation of contact ti², and (for example) relay ST¹ is operated, a circuit is closed from earth, contact bs¹, 15 relay FO, contacts aa¹ . . . aa²³ . . . stⁿ³, fo¹, st³, st¹³, st²³, c⁴, relay AA¹ to battery. Relay AA¹ operates and causes circuit operations to take place similar to those described for relay AA.

Upon the operation of relay TI, relays ST, 20 WA and A release, their circuits being opened at contacts ti², ti³ and ti⁶ respectively. Other operations are similar to those described in connection with Figure 2 and result in the issue of ticket, the release of relays IM and TI, registration of the bet, and the release of the ticket machine.

When a place bet is made, relay PB operates and operations similar to those already described take place. The operation of relay PD follows 30 that of relay A its circuit being completed from the earth at contact a¹ by way of contacts st⁶ and pb⁸. The operation of a second relay for a place bet is prevented owing to the bridging of terminals P and WP.

The circuit operations in the case of an attempted bet on a non-runner, resulting in the operation of relay C are also similar and will not therefore be described in detail. The part of the circuit, not shown, that extends from contacts aa¹ 40 and aa⁸ may be identical to that shown in Figure 2, contacts aa⁷ and aa⁸ corresponding to contacts a⁷ and a⁸ respectively. When relay C operates on its upper winding, it holds by way of contacts c³ and st² to the earth potential at contact pb⁵ or 45 the battery potential pb¹ according to whether the bet is for a win or for a place. Also, contact c⁴ disconnects relay AA and extends the chain circuit prior to the relapse of contact st³, and contact c¹ opens the circuits of both windings of 50 relay A.

Although it may be desirable to have arrangements similar to those described to operate in the event of failure in the chain circuit, the risk of failure may be reduced to an almost negligible 55 amount by duplicating the relay contacts and/or by the use of twin contacts, in which contact between the spring members is made at more than one point.

It will of course be understood that if it is not 60 desired to allow concurrent registration of different classes of bets, terminals W and P (Figures 2 and 6) may be short-circuited or, alternatively, only one common terminal, such as W, connected directly to contact a⁶, instead of by way of contact pb⁴, need be provided per chain circuit.

Other features of the system in connection with which my invention has been described are the subject of British patent application No. 2999/31.

Having now described my invention, what I 70 claim as new and desire to secure by Letters Patent is:—

1. An electric totalizer comprising a plurality of impulse transmitting stations, a chain of relays adapted to collect impulses therefrom by assum- 75

- ing a position corresponding to a station having an impulse to transmit and thereafter directly assuming a position corresponding to another station having an impulse to transmit, the said 5 chain of relays providing a path for the extension of an electric potential through contacts of relays associated with stations having no impulses to transmit to the winding of a relay associated with a station having an impulse to transmit, 10 and means to prevent the collection of an impulse from any one station being delayed indefinitely by the collection of a plurality of overlapping impulses from other stations.
2. An electric totalizer comprising a plurality 15 of impulse transmitting stations, a primary relay associated with each station adapted to operate when the station has an impulse to transmit, a secondary relay associated with each station adapted to operate as the result of the operation 20 of the primary relay in order to cause the registration of the impulse and the subsequent release of the primary relay, means whereby in the event of a plurality of the said primary relays being operated at the same time the associated secondary relays are constrained to await 25 their turn to operate according to a predetermined order of priority, and means to prevent
- 10 15 20 25

the reoperation of any of the said plurality of primary relays until all the associated secondary relays have operated.

3. An electric totalizer comprising a plurality 5 of impulse transmitting stations each adapted to transmit impulses of different classes, a primary relay associated with each station adapted to operate when the station has an impulse to transmit, a secondary relay associated with each station adapted to operate as the result of the operation 10 of the primary relay in order to cause the registration of the impulse and the subsequent release of the primary relay, means whereby in the event of a plurality of the said primary relays being operated at the same time, such of the secondary relays as are 15 associated with stations having the same class of impulse to transmit are constrained to await their turn to operate according to a predetermined order of priority, means to allow two of the 20 said secondary relays to be operated at the same time for the concurrent registration of impulses of different classes, and means to prevent the reoperation of any of the said plurality of primary relays until all the associated secondary relays 25 have operated.

FREDERICK LIMB
